UNITED STATES PATENT OFFICE.

LAZARD KAHN, OF HAMILTON, OHIO, ASSIGNOR TO E. & L. KAHN & BROS.,
OF SAME PLACE.

DESIGN FOR A SAD-IRON HEATER.

SPECIFICATION forming part of Design No. 25,438, dated April 28, 1896.

Application filed November 20, 1895. Serial No. 569,588. Term of patent 14 years.

To all whom it may concern:

Be it known that I, LAZARD KAHN, a citizen of the United States, residing at Hamilton, Butler county, Ohio, have invented and produced a new and original Design for Sad-Iron Heaters, of which the following is a specification, reference being had to the accompanying drawing, which is a perspective view of a sad-iron heater, showing my design.

○ The leading feature of my design consists in the sad-iron heater having the form of the frustum of a pyramid armed at its angles with outwardly-projecting ribs.

A is the sad-iron heater, whose form is that of the frustum of a pyramid.

B indicates the outwardly-projecting ribs with which the corners or angles of the heater are armed.

What I claim is—

The design for a sad-iron heater as herein shown and described.

LAZARD KAHN.
